UNITED STATES PATENT OFFICE.

JAMES K. BOYD, OF WILKINSBURG, PENNSYLVANIA.

COMPOUND RAIL.

1,265,422.

Specification of Letters Patent.

Patented May 7, 1918.

Application filed March 2, 1918. Serial No. 220,025.

To all whom it may concern:

Be it known that I, JAMES K. BOYD, a citizen of the United States, and resident of Wilkinsburg, in the county of Allegheny 5 and State of Pennsylvania, have invented certain new and useful Improvements in Compound Rails, of which the following is a specification.

My invention relates to the construction 10 of rails used in building the tracks of electric, steam and similar railways.

The weight of the rolling stock of railways has enormously increased in recent years, while the strength and durability of 15 the track rails, although being constantly increased in size, has not kept pace with the increase in the loads sustained by the rails.

One reason for this is because of the impossibility of increasing the size of the head 20 of the track rails and at the same time to "work" the metal of the rail head to the extent necessary to make the steel dense enough to have the desired wearing qualities with existing mill equipment.

25 One object of my invention is to provide a compound track rail of improved construction having novel means whereby the desired increase in strength, rigidity, and wearing qualities is obtained.

30 Another object of the invention is the provision in a compound rail of novel means whereby the load and side thrust of the rolling stock is transmitted from the rail head to the base flanges of the rail girder through 35 the clamping members and without undue strain upon the rail girder web and liability of "crescent breaks" in the rail girder is thereby avoided and overcome.

Another object of this invention is to provide 40 a compound track rail having improved means whereby the necessity of frequent repairs is avoided and overcome and the cost of maintenance of tracks employing such rails is lessened, and whereby renewal of the 45 wearing parts of the track rails is easily and quickly effected without disturbance or removal of the rails from the ties supporting the track rails on the road bed of the railway.

50 Another object of this invention is the provision of a compound track rail of improved construction and having novel means whereby the distribution of the metal in the rail is effected in such manner as to combine maximum strength and rigidity and

wearing qualities in a rail of given size or weight.

Another object of the invention is to provide a compound track rail of improved construction, wherein the metal of the several 60 parts of the rail is distributed to facilitate the rolling operation and to "work" the metal in the wearing parts of the rail so as to increase the strength and durability or resistance to wear of such wearing parts of the 65 rail.

A further object of the invention is to provide a compound rail having novel means whereby the parts of the rail are assembled and detachably held in assembled relation. 70

A still further object of my invention is the provision of a compound track rail having the novel constructions, arrangements, and combination of parts shown in the drawings, hereinafter described in detail, 75 and specifically pointed out in the appended claims.

Referring now to the drawings, forming part of this specification, Figure 1 is a sectional end elevation showing a compound 80 rail embodying my invention, the section being taken on the line I—I of Fig. 3.

Fig. 2 is a sectional end elevation taken on the line II—II of Fig. 3.

Fig. 3 is a side elevation on a smaller 85 scale, showing contiguous alined track rails as assembled and joined in constructing railway tracks employing my improved rail, and Fig. 4 is a similar side elevation showing contiguous alined track rails, constructed 90 in accordance with my invention. Fig. 4 is a continuation of Fig. 3, an intermediate and the abutting ends of adjoining rails being shown by connecting Figs. 3 and 4 on the line X—X of these figures. 95

In the accompanying drawings, the head A forming the wearing surface of my improved rail is shown supported upon the flanged base or girder B of the rail, being fastened to the girder by means of clamping members formed by the clamping clips C and clamping splice bars D. 100

The rail head A comprises a wearing surface 2 having integrally formed marginal flanges 3—3, the lower ends 4—4 of the 105 flanges 3 being turned outward, substantially at right angles to the other part of the flanges 3, and the flanges 3 forming a tapering groove in the under surface of the head A, the so-formed groove having inwardly 110

inclined or converging side surfaces 5, as is clearly shown in Figs. 1 and 2.

The girder or stringer B of the rail comprises a vertical web 6 having oppositely extending bottom flanges 7-7 and oppositely extending top flanges 8-8 at the ends thereof.

An integral projection or ridge 9 is provided on the girder B above the flanges 10 8-8, this projection having inwardly and upwardly sloping side surfaces 10-10 and having a contour which preferably is made to neatly fit within the recess or groove in the lower face of the rail head A and to have a surface contact therewith. (See Figs. 1 and 2.)

The flanges 7 and 8 taper, the sloping upper surface 11 of the bottom flanges 7 and under surface 12 of the top flanges 8 being 20 inclined at opposite angles to provide the clearance necessary in the rolling operation. The ends 4-4 of the flanges 3 on the rail head A also taper, the sloping upper surface 13 thereof being inclined and extending in 25 a plane parallel to the plane of the upper surfaces 11 of the bottom flanges 7.

The clamping clips C by which the rail head A is detachably secured in place on top of the girder B have a web 14 whose end or 30 girder engaging surfaces 15, 16 are oppositely inclined at the same angle as the upper surface 11 of the bottom flanges 7 and under surface 12 of the top flanges 8 of the girder B, and the upper edge of the web 14 35 has a bent flange 17 which coacts with the end of the web 12 in forming a double taper groove 18. The sloping side surfaces 16 and 20 of the grooves 18 are oppositely inclined and extend in planes parallel with the surface 13 of the rail head A and surface 12 of the girder flanges 8. The grooves 18 are 40 made deep enough to permit of adjustment so as to tightly wedge the head A in place on the girder B when the nuts 21 are tightened on the fastening bolts 22. Registering holes 23 and 24 are provided in the web of the clips and rail girder B for the bolts 22.

The clamping splice plates D have a web 25 with a foot 26 on one and a flange 27 on the other edge thereof. The sloping surfaces 28 and 29 of the splice plates D (like the corresponding surfaces of the clips C) are oppositely inclined, and have an included angle the same as that between the surfaces 11 and 12 of the girder B.

The flange 27 on the upper edge of the splice plates D, is bent to form a double taper groove 30, being formed in the same manner as the groove in the clips C, and for 60 the same purpose, and registering holes 23, 24 are provided in the web of the splice plates D and girder B for the fastening bolts 22.

The heads and the girders may and preferably will be made of equal length, and as-

sembled to form broken joints, *i. e.*—the joint between the abutting ends of the rail heads A will not be in line with the joint between the abutting ends of the rail girders B. (See Figs. 3 and 4.)

The splice plates D, as will be seen in Figs. 3 and 4, are of sufficient length to provide for two bolts for each end of abutting rail girders, while the clips C preferably are comparatively short, and of only sufficient length to receive one clamping bolt. It will be obvious, however, that they may be made longer when found desirable or necessary. The clamping splice plates D fasten the rail heads A to the girders B adjacent to the 70 abutting ends of adjoining girders, and a series of the clips C will be employed to fasten the head to the girders at separated points between the splice plates D located at the opposite ends of the girders.

It will be noted that the surfaces 15, 28 of the clips C and splice plates D bear on the upper inclined surfaces 11 of the bottom flanges 7 of the girder B, and that the loads put upon the rail head will be transmitted 75 through the clips and splice plates to the bottom flanges of the rail and, through the bottom flanges 7, to the ties supporting the track rails. This is an important feature of my invention and by such construction the rail is strengthened and stiffened, so as to readily resist the enormous side thrust put upon the rails by the rolling stock and to substantially eliminate the occurrence of crescent breaks in the base flanges of the 80 rails, an ever present danger in both T-head and in compound rails, as heretofore made.

Care should be taken to make the spacing of the bolt holes 24 in the web of the rail girder, a multiple of the distance between the bolt holes 23 in the splice plates D. By arranging the holes in this manner, a pair of the splice plates D may be applied to the rail to temporarily fasten together the 95 ends of a broken rail girder or rail head by 100 substituting a pair of splice plates D for two or more of the clamps C.

The advantages of my invention will be appreciated by those skilled in the art. The head of the rail is designed so as to be 105 readily rolled, and the contacting surfaces between the head A and girder B are of a contour which enables the parts to be made within the usual working limits and at the same time provide a slight "draw" on the 110 parts in tightening the clamps and clamping splice plates on the rail.

The rail head is of comparatively light section, so that it is possible to get sufficient "work" on the metal in rolling the head 115 necessary to produce the desired dense metal having the necessary wearing qualities.

The composition of the metal in the head, which can be different from that in the base or girder, may be ordinary rail steel or of 120

high carbon, alloy, or heat treated steels, of a quality not possible to use with ordinary integrally formed track rails. The girder may be made of any grade of steel which 5 will afford the necessary strength and elasticity without taking into account the wearing qualities, as is necessary in an integrally formed rail.

Modifications in the construction and arrangement of the parts may be made without departing from my invention as defined in the appended claims.

I claim:-

1. In a compound rail, the combination 15 of a rolled metal head having integral flanges, said flanges forming a longitudinal groove in the bottom surface of the head and having tapering horizontally extending lower edges, an integral rolled metal 20 girder having a web and tapering horizontally extending top and bottom flanges, clamping members for securing the rail head on the girder, said clamping members having sloping surfaces engaging with oppositely sloping surfaces on the tapering flanges of the head and the top and bottom flanges of the girder in securing the rail head to the girder, and means for fastening the clamping members in holding engagement with the flanges. 25

2. In a compound rail, the combination 35 of a rolled metal head having integral flanges, said flanges forming a longitudinal groove in the bottom surface of the head and having tapering horizontally extending lower edges, an integral rolled metal 40 girder having a web and tapering horizontally extending top and bottom flanges, a series of pairs of clamping members for securing the rail head on the girder, said clamping members having sloping surfaces engaging with oppositely sloping surfaces on the tapering flanges of the head and the top and bottom flanges of the girder 45 in securing the rail head to the girder, part of said series of pairs of clamping members being arranged to connect the abutting ends of said girders, and means for fastening the clamping members in holding engagement with the flanges. 50

3. In a compound rail, the combination 55 of a rolled metal head having integral flanges, said flanges forming a longitudinal groove in the bottom surface of the head and having tapering horizontally extending lower edges, an integral rolled metal girder having a web and tapering horizontally extending top and bottom flanges, a series of pairs of clamping members for securing the 60 rail head on the girder, said clamping members having sloping surfaces engaging with oppositely sloping surfaces on the tapering flanges of the head and the top and bottom flanges of the girder in securing the 65 rail head to the girder, part of said series

of pairs of clamping members being arranged to connect the abutting ends of said girders and said heads, and means for fastening the clamping members in holding engagement with the flanges. 70

4. In a compound rail, the combination 75 of a rolled metal head having integral flanges, said flanges forming a longitudinal groove in the bottom surface of the head and having tapering horizontally extending lower edges, an integral rolled metal girder having a web and tapering horizontally extending top and bottom flanges, a ridge on said girder above the top flanges thereof, said ridge having converging sides fitting 80 the inclined side surfaces of the groove in said rail head, clamping members for securing the rail head on the girder, said clamping members having sloping surfaces engaging with oppositely sloping surfaces on the tapering flanges of the head and the top and bottom flanges of the girder in securing the rail head to the girder, and means for fastening the clamping members 85 in holding engagement with the flanges. 90

5. In a compound rail, the combination 95 of an integrally formed rolled steel girder, said girder having a web and tapering oppositely extending top and bottom flanges with a longitudinal ridge above the top flanges of the girder, said ridge having upwardly and inwardly converging sides, an integrally formed rolled steel head on top of said girder, said head having a longitudinal groove on the bottom thereof of the same contour as said ridge and outwardly extending tapering flanges at the lower edges of the head, a series of clip fastenings 100 for securing the head to the girder, said fastenings having a double taper groove in one side engaging with the oppositely inclined surfaces of the flanges on said head and top flanges of the girder, and having a foot engaging the inclined upper surface of the lower flange of said girder, and means 105 for fastening the clips in holding engagement with the flanges. 110

6. In a compound rail, the combination 115 of an integrally formed rolled steel girder, said girder having a web and tapering oppositely extending top and bottom flanges with a longitudinal ridge above the top flanges of the girder, said ridge having upwardly converging sides, an integrally formed rolled steel head on top of said 120 girder, said head having a longitudinal groove on the bottom thereof of the same contour as said ridge, and outwardly extending tapering flanges at the lower edges of the head, a series of clip fastenings for 125 securing the head to the girder, said clips having a double taper groove in one side engaging with the oppositely inclined surfaces of the flanges on said head and top flanges of the girder, and having a foot en- 130

1. gaging the inclined upper surface of the lower flange of said girder, registering holes in said clips and girder and bolts extending through said registering holes for 5 fastening said clips to the girder in holding engagement with the flanges on the head and girder.
2. In a compound rail, the combination of a flanged head having a longitudinal groove 10 in the bottom surface thereof, said groove having inclined sides, a flanged girder having a longitudinal ridge on its upper surface, said ridge having the contour of said groove, and a series of pairs of clips for 15 fastening the head on the girder, said clips having a groove with inclined sides in one face thereof in which the contacting flanges on the head and girder are positioned, and means for fastening the clips to the rail 20 girder, said means being arranged to draw the clips into tight holding engagement with the contacting flanges of said head and girder.
3. In a compound rail, the combination of 25 a flanged head having a longitudinal groove in the bottom surface thereof, said groove having inclined sides, a flanged girder having a longitudinal ridge of the contour of said groove, and a series of pairs of clips 30 for fastening the head on the girder, said clips having a groove with inclined sides in one face thereof in which the contacting flanges on the head and girder are positioned, part of said clips forming clamping 35 splice plates for connecting the abutting ends of the rail girders, and means for fastening the clips to the rail girder, said means being arranged to draw the clips into tight holding engagement with the contacting 40 flanges of said head and girder.
4. In a compound rail, the combination of an integral rolled steel girder having a web and oppositely extending top and bottom flanges and a longitudinal ridge above the 45 top flanges of the girder, said ridge having converging sides, an integrally formed rolled steel head on top of said girder, said head having a longitudinal groove on the bottom thereof of the same contour as said 50 ridge and having outwardly extending flanges at the lower edges of the head, a series of clip fastenings for securing the flanges on the head to the top flanges of said girder, said clips having a double taper 55 groove in one side engaging with the oppositely inclined surfaces of adjacent flanges on said head and girder to secure the head on the girder, and means for fastening the rail clips in holding position on the girder.
5. In a compound rail, the combination 60 of a rolled metal head having integral flanges, said flanges forming a longitudinal groove in the bottom surface of the head and having tapering horizontally extending lower edges, an integral rolled metal girder 65 having a web and tapering horizontally extending top and bottom flanges, clamping members for securing the rail head on the girder, said clamping members having sloping surfaces engaging with oppositely sloping surfaces on the tapering flanges of the head and the top flanges of the girder in securing the rail head to the girder, and means for fastening the clamping members in holding engagement with the flanges. 75
6. In a compound rail, the combination of a rolled metal head having integral flanges, said flanges forming a longitudinal groove in the bottom surface of the head and having tapering horizontally extending lower edges, an integral rolled metal girder 80 having a web and tapering horizontally extending top and bottom flanges, a ridge on said girder above the top flanges thereof, said ridge having converging sides fitting 85 the inclined side surfaces of the groove in said rail head, clamping members for securing the rail head on the girder, said clamping members having sloping surfaces engaging with oppositely sloping surfaces on the 90 tapering flanges of the head and the top flanges of the girder in securing the rail head to the girder, and means for fastening the clamping members in holding engagement with the flanges. 95
7. In a compound rail, the combination of an integrally formed rolled steel girder, said girder having a web and tapering oppositely extending top and bottom flanges with a longitudinal ridge above the top flanges of the girder, said ridge having up- 100 wardly and inwardly converging sides, an integrally formed roller steel head on top of said girder, said head having a longitudinal groove on the bottom thereof of the same 105 contour as said ridge and outwardly extending tapering flanges at the lower edges of the head, a series of clip fastenings for securing the head to the girder, said fastenings having a double taper groove in one 110 side engaging with the oppositely inclined surfaces of the flanges on said head and top flanges of the girder, and means for fastening the clips in holding engagement with the flanges. 115
- In testimony whereof I have hereunto set my hand.
- JAMES K. BOYD.
